[57] CLAIM

The ornamental design for an ice making machine, as shown and described.

DESCRIPTION

FIG. 1 is a front elevational view of an ice making, showing our new design;

FIG. 2 is a right side elevational view thereof;

FIG. 3 is a rear elevational view thereof;

FIG. 4 is a top plan view thereof;

FIG. 5 is a bottom plan view thereof;

FIG. 6 is an enlarged perspective view thereof; and,

FIG. 7 is another enlarged perspective view thereof showing a door in its opened state.

The surface(s) or portion(s) of the article not shown in the drawing or described in the specification form(s) no part of the claimed design.
